UNITED STATES PATENT OFFICE.

PETER E. MAGGINI, OF LOS ANGELES, CALIFORNIA.

MACHINE FOR MAKING OLIVE-OIL.

No. 890,079.

Specification of Letters Patent. Patented June 9, 1908.

Application filed August 16, 1907. Serial No. 388,780.

To all whom it may concern:

Be it known that I, PETER E. MAGGINI, a citizen of the United States, residing at Los Angeles, California, have invented new and useful Improvements in Machines for Making Olive-Oil, of which the following is a specification.

An object of this invention is to simplify machines for making olive oil and to construct said machines in a stronger and more compact form, with a view to economizing floor space and of firmly supporting the tank wherein the olives are crushed so that the apparatus will not be damaged by the jar resulting from the movements of the heavy crushing rollers employed to loosen the pulp from the pits.

The invention consists essentially in the construction, combination and arrangement of the several parts as will be hereinafter fully described in the specification, illustrated in the drawings, and specifically pointed out in the claims.

Referring to the accompanying drawings Figure 1, is a longitudinal section of the complete apparatus, on line x^1-x^1 , Fig. 2. Fig. 2 is a broken view thereof omitting the tank for supplying water to the crushing receptacle. Fig. 3 is a side view of a portion of one of the tanks, illustrating an improved double gate used in connection with said tank.

1 designates an upper tank or hopper to which the olives are supplied and 2 a tank for supplying water to tank 1. In tank 1 are mounted a plurality of crushing rollers 3, desirably three in number, carried by rotary head 4 fixed to and turned by upright shaft 5.

6 designates an opening in the bottom of hopper 1, said opening being opened or closed by slide 7, and leading into tank 8, where stirring arms 9 and 10 provided with stirring loops or fingers 11 are attached to shaft 5.

12 designates a spout adapted to deliver mixed water and pulp from the upper portion of tank 8 to tank 13, which is located adjacent to and at a lower level than tanks 8 and 15.

14 and 14' designate openings in the bottom of tank 8 for allowing the pits to pass into lower tank or compartment 15. Said compartment 15 is provided near its bottom with an opening 16 controlled by an inner

perforated slide 17 and an outer imperforate slide 18.

19 is an opening on the opposite side of compartment 15 to be used as an aid to removing pits from compartment 15. Said opening 19 may be controlled by a slide 19'.

20 is a gate controlled by slide 20' through which the oil and pulp may be raked off from the top of tank 13 for further treatment in a press (not shown).

21 is a plug which may be removed from the bottom of tank 13 when it is desired to drain the water off from said tank.

22, 23 and 24 designate legs on which the apparatus is supported.

25 is a pedestal for supporting the driving shaft 26 and the driven shaft 5. Said driving shaft 26 may carry a double pulley 27 at the outer end and a beveled gear 28 at the inner end. Said gear 28 meshes with beveled gear 29 fixed to the lower end of driven shaft 5.

30 is a conical sleeve surrounding the lower portion of shaft 5 and forming a water-tight jacket therefor. Said sleeve 30 may be cast integral with the bottom of tank 15 or may be otherwise formed if desired. Conical sleeve 30 forms a housing for said shaft and preferably extends up to near the top of tank 8, the stirring arms 9 and 10 being upwardly bent at their inner ends and attached to a shaft 5 at a point above the top of sleeve 30.

31 is a platform supported by legs 22 and 23 upon which superposed tanks 15, 8 and 1 are mounted.

32 is a conical rise from the center of the bottom of hopper 1 to form a bearing for the upper end of shaft 5. Said rise extends above the level of the water in hopper 1 and at its lower end provides room for the agitating arms 9 and 10 to be attached to shaft 5 at sufficient height so that the conical sleeve 30 may extend above the level of fluid in tank 8. It is to be understood that in the operation of the apparatus openings 16 and 19 of lower tank 15 are normally kept tightly closed so that the level of the pulp and water in tank 8 is kept above stirring arms 9 and 10.

The compartment 8 is covered and enclosed on all sides and therefore forms an excellent agitating chamber because fluid cannot splash out on the floor and dust cannot enter to injure the olive oil. A firm, com-

pact construction and one adapted to keep dust away from the olive pulp, results from employing the plurality of superposed communicating tanks 1, 8 and 15 in combination 5 with the upright shaft 5, said shaft directly operating both crushing or pulp-loosening means and the agitating means which entirely separate the pulp from the pits in tank 8. Tanks 8 and 15 may be separated by a 10 partition 15' seated in an annular step 15" at the top of tank 15.

A brief statement of the operation is as follows: Olives are fed to tank 1, and water added from tank 2 through faucet 2'. The 15 machine being put in operation, crushing wheels 3 carried by rotary head 4 are caused by shaft 5 to travel around the hopper and crush the pulp, loosening it from the pits. Mingled pulp, pits and water pass through 20 opening 6, controlled by slide 7, into compartment 8 where stirring arms 9 and 10 having fingers 11 agitate the same. The pulp and oil rise and pass out through spout 12 into tank 13, while the pits and water pass 25 through openings 14 and 14' into compartment 15. Opening 16 is controlled by an inner perforated slide 17 and an outer imperforate slide 18. When slide 18 only, is raised, only the water escapes into tank 13. When 30 both slides 17 and 18 are raised, the pits may be withdrawn through opening 16. The water in tanks 8 and 15 is occasionally drawn off when it is desired to remove the pits from lower tank 15. Such portion of the pits as 35 may be removed through gate 16 may be drawn into suitable receptacle (not shown) held in front of opening 16 while gates 17 and 18 are raised and the pits pulled out from tank 15 by means of any suitable instrument. 40 19 is another opening to assist in removing pits from tank 15.

20 is a gate through which the oil and pulp are raked off from the top of delivery tank 13, for further treatment in a press (not 45 shown).

3' designates scrapers for clearing the rollers of any pulp that may stick to them.

31' designates a bearing plate secured to the bottom of platform 31 to afford an additional bearing for shaft 5.

I claim:

1. In a machine for making olive oil, in combination, a hopper, crushing means to operate therein, an inclosed tank underneath 55 said hopper and communicating therewith, suitable outlets being provided for said tank, and a double gate for controlling exit from one of said outlets, said gate comprising an inner foraminated slide and an independently 60 movable outer imperforate slide.

2. In a machine for making olive oil, in combination, a hopper, crushing means in said hopper, an inclosed agitating chamber

beneath said hopper and communicating therewith, means for agitating olives in said 65 chamber to separate the pulp and pits, a pit receptacle beneath said agitating chamber and communicating therewith by means of small openings adapted to admit pits only, outlet means adapted to deliver mixed pulp 70 and water from the upper portion of the agitating chamber, outlet means communicating with the lower portion of said pit receptacle, and a delivery tank beneath said outlets and adapted to receive the discharge coming from 75 both of said outlet means.

3. In a machine for making olive oil, in combination, a tank inclosed on all sides, a transverse partition in said tank dividing the same in upper and lower chambers, a hopper 80 above said tank and communicating therewith, crushing means in said hopper, agitating means in said upper chamber, a vertical shaft extending through both of said chambers to operate said agitating means and 85 said crushing means, means below the lower chamber for operating said shaft, and a delivery tank located adjacent to and at a lower level than both of said chambers, there being outlet means to deliver the material 90 operated upon from both of said chambers to said delivery tank.

4. A machine for making olive oil provided with a plurality of superposed tanks, crushing means in one of said tanks, agitating 95 means in another of said tanks, and a common shaft to operate said crushing means and said agitating means.

5. In a machine for making olive oil, in combination, a hopper provided with a rise 100 in the center of the bottom thereof, a tank beneath said hopper and supporting the same, an upright shaft, a housing for said shaft extending nearly to the top of said tank, stirring arms attached to said shaft 105 above said housing, crushing means operating in said hopper and attached to said shaft above said rise, and means beneath said tank for rotating said shaft.

6. In a machine for making olive oil, in 110 combination, a hopper, crushing means to operate therein, a tank underneath said hopper and communicating therewith, an outlet being provided for said tank, and a double gate to control said outlet, said gate comprising an inner slide having openings therethrough and an independently movable outer slide adapted to entirely close the outlet. 115

7. In a machine for making olive oil, in combination, a tank having upper and lower 120 chambers, a hopper communicating with said upper chamber, crushing means in said hopper, agitating means in said upper chamber, a vertical shaft to operate said agitating means and said crushing means, means for 125 operating said shaft, and a delivery tank,

there being outlet means to deliver material from said chambers to said tank.

8. In combination, a series of superposed communicating tanks, crushing means in an upper tank, and agitating means in an intermediate tank, said intermediate tank having bottom openings adapted to discharge pits into a tank therebeneath.

In testimony whereof I have hereunto

signed my name in the presence of two ¹⁰ subscribing witnesses at Los Angeles, in the county of Los Angeles and State of California, this 10th day of August 1907.

PETER E. MAGGINI.
